UNITED STATES PATENT OFFICE.

HENRY FACHS, OF NEW YORK, N. Y.

CUTTING-MACHINE.

1,025,741.

Specification of Letters Patent.

Patented May 7, 1912.

Application filed June 22, 1910. Serial No. 568,277.

To all whom it may concern:

Be it known that I, HENRY FACHS, a citizen of the United States, and a resident of the city of New York, Woodside, borough 5 of Queens, in the county of Queens and State of New York, have invented a new and Improved Cutting-Machine, of which the following is a full, clear, and exact description.

10 My invention relates generally to cutting machines and more particularly it involves a construction wherein the material passing through the machine is properly cut, there being other means coöperating therewith whereby the material supplied to the machine is moved into position beyond the cutters whereby succeeding portions may be cut.

15 In most machines in present use, the material is cut by an operation entirely independent of the general operation of the machine, thus involving considerable time and labor. Furthermore, the gummed strip, after being moistened, must oftentimes be 20 repeatedly handled before the same is cut, and in this manner a large amount of the gum on the strip is removed therefrom and the hands are left in a sticky and unclean condition. In my machine, the material is 25 cut in such a manner that it may be cut to any length desired, and the method of cutting is so conducted that the stock end or end of material from which a piece has been 30 severed, is automatically fed into the machine as the cutting means are returned to 35 their initial position.

Reference is to be had to the accompanying drawings, constituting a part of this specification, in which similar characters of 40 reference denote corresponding parts in all the views, and in which—

Figure 1 is a side elevation of my machine with the operating parts in initial position; Fig. 2 is a similar view, showing the operating parts in final position, the stock reel being cut away; Fig. 3 is an end view of my machine and looking in the direction of the arrow shown in Fig. 2, the tank being removed to disclose the underlying structure; 45 Fig. 4 is a fragmentary, sectional view disclosing the cutting means and the relative position of the moistening rollers; Fig. 5 is a detail side elevation of the cutting means; and Fig. 6 is a detail sectional view of the 50 adjustable feeding reel.

Referring more particularly to the vari-

ous views, a frame 10 is provided, consisting of uprights 11 secured to a base 12 and joined by a cross piece 13. Upwardly-extending brackets 14 are secured to the frame 10, and an adjustable, hinged platform, or table 15, is slidably mounted thereon. Mounted to turn on the frame 10 and preferably disposed one over the other, are similar moistening rollers 16, having their peripheral surfaces contacting, and the lower roller provided with a crank 17 and handle 18 for turning the roller, thus also revolving the upper roller in an opposite direction to the lower roller. Bars 19, provided with 60 eyes 20 engaging the upper roller 16, are vertically disposed on both sides of the uprights 11 and inclosed by compression springs 21, with the said bars 19 slidable in sleeves 22 secured to an adjusting bar 22, 65 capable of being vertically moved by an adjusting screw 23, to adjust the upper roller 16 relative to the lower roller. With the bars 19 disposed as mentioned and engaged by the springs 21, the upper roller 16 is at 70 all times pressed downwardly by the springs, and when material is passed between the rollers a force proportional to the thickness of the material and the strength of the springs, will at all times press the upper 75 roller toward the lower roller, so that when the rollers turn the material will substantially bind with the rollers and thus be fed toward the end of the machine, while at the same time, it will be evenly and accurately 80 moistened.

An operating lever 24, is pivotally mounted on one of the uprights 11 at 25, and is provided with a lug 26 arranged to slide in a slot 27 in a knife blade 28, pivotally 95 mounted on a second knife blade 29, rigidly secured to the uprights 11. Guides 30 are provided on the frame 10, and a carriage 31 is mounted to slide horizontally thereon and provided with a spring-controlled gripping bar 32, as will be easily seen in Figs. 3 and 4. A connecting bar 33 is pivotally mounted on the carriage 30 and provided with a slot 34 in which a pin 35 of a bar 36 is mounted to slide. An outwardly-projecting pin 37 is 100 secured to the bar 33 and adapted to be engaged by a projecting finger or lug 38 on the lever 24. An outwardly-projecting pin 39 is secured to the lever 24 and adapted to move in a slot 40 of the bar 36, and a pawl 41 105 mounted to swing on the bar 36 is adapted to engage a ratchet 42 rigidly mounted on

the crank shaft of the crank 17. For the purpose of facilitating the return movement of the lever 24 and the operative parts connected therewith, a spring 43 is secured to the lever 24 and the frame 10. In order to keep the roller 16 constantly moist, a tank 44 is arranged on the frame and provided with a perforated delivery pipe 45, the feed to the said pipe being substantially regulated by a valve 46 disposed adjacent to the inlet 47. An adjustable reel 48 is mounted on a bracket 49 and consists of a rod 50 secured to a disk 51 and mounted to slide in a sleeve 52 secured to a second disk 53, the said rod and sleeve being mounted to slide in a bearing 54 of the bracket 49 and removably held on the bracket by a set screw 55.

In the operation of my device, if it is desired to employ the machine for moistening and cutting paper, a roll of gummed paper is mounted on the reel 48, as will be easily seen in Fig. 4. The end of the roll is then taken and passed under the gripping bar 32, intermediate the knife blades 28 and 29 and is then passed between the rollers 16 which have been previously moistened by water contained in the tank 44. The crank handle 18 is now operated to turn the rollers, and as they revolve the strip of paper passes therebetween and is thoroughly moistened. When the desired length of strip has been moistened, the handle of the operating lever 24 is grasped and moved forwardly. As the lever is operated, the lug 26, operating in the slot 27 of the knife blade 28, moves the knife blade upwardly, and as the strip is disposed between the knife blades 28 and 29, the said strip will be severed from the roll when the knife blades co-act. Now, in order to secure a clean cut and to re-arrange the feeding of the strip into the machine, as the lever 24 is moved as mentioned, the carriage 31 is operated to move horizontally rearward on the guides 30 by the pin 39 of the lever 24, operating in the slot 40 of the bar 36. As the carriage is thus moved, the gripping bar 32 grips the paper and pulls the same taut and stiff, thus exposing a clean, smooth and unruffled surface for the knife blades 28 and 29. Now it will be noticed that after the moistened strip has been severed from the roll, the end of the roll will be disposed intermediate the knife blades and the gripping bar, and, as will be readily understood, the feeding operation of the end of the roll toward the rollers 16 is broken or inoperative, as the said end of the roll is in no manner in operative engagement with the rollers. To overcome this deficiency and re-establish the feed, the lever 24 is released and as the same springs back to normal position, owing to the tension of the spring 43, the carriage 31 is moved toward the rollers 16 and consequently the end of the roll is again brought into engagement

with the rollers. But in order to absolutely insure proper operation, the pawl and ratchet members are brought into use. As the lever moves back to its normal position, thus carrying the carriage with it, as has been mentioned, the pawl 41 engages the ratchet wheel 42, and as the lower part of the lever is moving toward the ratchet when the pawl engages the ratchet, it turns the same, thus also turning the shaft on which the lower roller is secured. As the roller turns, the end of the roll is again made to pass between the rollers, the crank handle is again turned to moisten the strip unreeled from the roll and the cutting operation, heretofore explained, is again resorted to when the strip has been moistened to the desired length.

By using the adjustable reel described, various sized rolls can be mounted on the same reel, as the width of the reel can be easily varied at any time.

In setting forth the construction and operation of my improved cutting means I have illustrated a machine embodying moistening rollers and have described these moistening rollers in connection with the cutting devices, it being apparent, however, that the cutting device may be used by itself and apart from any moistening rollers, such use being comprehended by the spirit of the invention.

Having thus described my invention, I claim as new and desire to secure by Letters Patent:

1. A device of the class described, comprising a frame, an operating lever movably carried thereby, a cutting blade movably carried by the frame, means on the lever adapted to engage the blade in order to move it, a carriage movably carried on the frame and provided with a spring-controlled bar adapted to engage an end portion of a supply of paper, together with means carried by the carriage and adapted for engagement with the said lever whereby movement of the lever will move the carriage.

2. A device of the class described, comprising a frame, a lever movably carried thereby, a spring-controlled cutting blade carried by the frame, means on the lever adapted for engagement with the blade in order to move it, a carriage slidably supported on the frame and provided with a spring-controlled gripping bar, a projecting finger on the lever, and means carried by the supporting means of the carriage and adapted to engage the said finger, whereby movement of the lever moves the carriage.

3. A device of the class described, comprising a frame, an operating lever movably carried by the frame, a finger projecting from the lever, a cutting blade carried by the frame, another blade movably supported adjacent thereto, means on the lever adapted

to engage the movable blade to actuate it, a carriage having a spring-controlled gripping bar thereon slidably carried by the frame, together with means in engagement 5 with the carriage and adapted for engagement by the said finger, whereby movement of the lever will move the carriage.

4. A device of the class described, comprising a frame, an operating lever carried thereby, a cutting blade movably carried by the frame, means on the lever adapted to engage the blade, whereby movement of the lever moves the blade, a carriage having a gripping bar thereon slidably supported on 15 the frame, members pivotally carried on the frame and in engagement with the carriage, together with means on the lever adapted to engage the said pivotally carried members, whereby the carriage may be moved.

20 5. A device of the class described, comprising a frame, a blade carried thereby, a movable blade adjacent the first blade and adapted to coöperate therewith, a carriage slidably supported on the frame, a gripping bar on the carriage, movable members carried by the frame and in engagement with the carriage, together with a lever also carried by the frame and having means thereon adapted to engage the said movable blade, 25 and other means adapted to engage the movable members engaging the carriage, whereby movement of the lever moves the said blade and also the carriage.

6. A device of the class described, comprising a frame, a blade movably supported thereon, a slot adjacent one end of the blade, a carriage slidably supported on the frame, a spring-controlled gripping bar on 35 the carriage, a movable connecting bar in engagement with the frame and the carriage, a lever movably supported on the frame, means on the lever adapted to engage the slot in the said blade, and other means on the lever adapted to engage the said connecting bar, whereby movement of the lever will move the blade and the carriage.

7. A device of the class described, comprising a frame, a blade pivotally supported thereon, a carriage slidably supported on the 50 frame, a spring-controlled gripping bar on the carriage, a movable connecting bar in engagement with the frame and the carriage, a lever movably supported on the frame, a lug on the lever adapted to engage the said blade, and a finger on the lever adapted to engage the said connecting bar, whereby movement of the lever moves the blade and the carriage.

8. A device of the class described, comprising a frame, a blade movably carried by the frame, a carriage slidably supported on the frame, a spring-controlled gripping bar on the carriage, a lever pivotally supported at an intermediate portion by the frame, a 65 movable member in engagement with the

frame and the said carriage, means intermediate the point of pivotal support of the lever and one end thereof adapted to engage the said blade, and other means adjacent the aforesaid end of the lever adapted to engage 70 the said movable member, whereby movement of the lever moves the blade and the carriage.

9. A device of the class described, comprising a frame, a blade on the frame, means for pivotally supporting it at one end, a slot adjacent the other end, a carriage slidably supported on the frame, a spring-controlled gripping bar on the carriage, a connecting bar pivotally supported at one end on the frame, the other end being in engagement 75 with the carriage, a lever movably supported on the frame and having means thereon for engagement with the slot in the said blade, and other means for engagement with the said connecting bar, whereby movement of the lever will move the blade and also the carriage.

10. A device of the class described, comprising a frame, a blade on the frame, means for pivotally supporting it at one end, a slot adjacent the other end, a carriage slidably supported on the frame, a spring-controlled gripping bar on the carriage, a connecting bar pivotally supported at one end on the frame, the other end being in engagement 90 with the carriage, a projecting pin on the bar, a lever movably supported on the frame and having a lug for engagement with the slot in the said blade, and other means on 100 the lever for engagement with the projecting pin, whereby movement of the lever will move the blade and the carriage.

11. A device of the class described, comprising a frame, a blade carried by the frame, another blade pivotally supported on the frame adjacent the first blade, a slot adjacent one end of the second blade, a carriage mounted on the frame, means for slidably supporting it thereon, a spring-controlled gripping bar on the carriage, a connecting bar pivotally supported at one end on the frame, the other end being in engagement with the carriage, a projecting pin on 105 the bar, a lever carried by the frame, a lug on the lever adapted to engage the slot in the said blade, a finger on the lever, and means on the said bar with which the finger is adapted to engage, whereby as the lever is moved the blade is operated and the carriage is moved.

12. A device of the class described, comprising a frame, a blade carried by the frame, another blade pivotally supported on the frame and adjacent the first blade and adapted to coöperate therewith, a slot adjacent one end of the second blade, a carriage mounted on the frame, means for slidably supporting it, a gripping bar on the carriage, a spring in engagement with the bar, 125

a connecting bar pivotally supported at one end on the frame, the other end being in engagement with the carriage, a pin on the bar and projecting laterally therefrom, a lever 5 carried by the frame, a lug on the lever, adapted to engage the said slot in the blade, a finger on the lever, there being a projecting pin on the said connecting bar with which the said finger is adapted to engage, 10 whereby when the lever is moved the blade may be operated and the carriage may be moved.

13. A device of the class described, comprising a frame, a blade secured to the 15 frame, another blade movably supported adjacent the first blade and adapted to coöperate therewith, a slot in the second blade, a lever movably carried by the frame, and means on the lever adapted to engage the 20 slot in the blade, whereby when the lever is moved the said blade will be operated.

14. A device of the class described, comprising a frame, a blade carried by the frame, another blade pivotally secured to the 25 frame adjacent the first blade and adapted to coöperate therewith, a slot adjacent one end of the second blade, a lever carried by the frame and having a lug thereon adapted to engage the said slot in the blade, whereby 30 when the lever is moved the blade will be operated.

15. A device of the class described, comprising a frame, a carriage slidably supported on the frame, a spring-controlled 35 gripping bar on the carriage, a connecting bar having one end in engagement with the frame and the other end in engagement with the carriage, a lever carried by the frame, a finger on the lever, and means on the said 40 bar, with which the finger is adapted to engage, whereby movement of the lever will reciprocate the carriage.

16. A device of the class described, comprising a frame, a carriage slidably supported on the frame, a spring-controlled 45 gripping bar on the carriage, a connecting

bar having one end in engagement with the frame and the other end engaging the carriage, a projecting pin on the bar, a lever carried by the frame, having means thereon for engagement with the said pin, whereby as the lever is moved the carriage will be reciprocated.

17. A device of the class described, comprising a frame, a carriage slidably supported on the frame, a gripping-bar on the carriage, a spring on the carriage in engagement with the bar, a connecting bar having one end in engagement with the frame and the other end engaging the carriage, a pin projecting from the bar, a lever carried by the frame, and a finger on the lever for engagement with the said pin whereby when the lever is moved the carriage may be reciprocated.

18. A device of the class described, comprising a frame, rolls on the frame, a carriage having a spring-controlled gripping bar thereon, co-acting knife blades carried by the frame and located between the said rolls and the said carriage, a lever carried by the frame, means on the lever adapted to engage one of the said blades in order to actuate it, a finger on the lever, movable means engaging the frame and the carriage and adapted to be engaged by the said finger whereby the carriage is moved, a ratchet arranged to turn with one of the said rolls, a pawl engaging the ratchet, a bar engaging the pawl, and means carried on the frame 80 and engaging the said bar adapted to be actuated by the lever, whereby movement of the lever in one direction will turn the said rolls.

In testimony whereof I have signed my 85 name to this specification in the presence of two subscribing witnesses.

HENRY FACHS.
